UNITED STATES PATENT OFFICE.

GEORGE L. REICHELM, OF NEW YORK, N. Y., ASSIGNOR TO THE GASIFIER COMPANY; OF ELIZABETH, NEW JERSEY, A CORPORATION OF NEW JERSEY.

MEANS FOR PRODUCING GAS.

Application filed February 7, 1920. Serial No. 356,880.

My invention relates to a means for producing gas.

One object of my invention is to increase the production of combustible gas from a given quantity of liquid or solid fuel.

Another object is to provide a novel and efficient method for extracting gas from a solid or liquid fuel, or for expanding a liquid or solid fuel into a fixed gas.

Another object is to provide simple and efficient means for practising the method hereinabove mentioned.

These and other objects are accomplished by means of the method and apparatus disclosed on the accompanying sheet of drawings, in which—

Figure 1 is a vertical sectional view of apparatus embodying my invention and used in the production of gas;

Figure 2 is a sectional view taken in the plane of line 2—2 of Figure 1; and

Figure 3 is a sectional view taken in the plane of line 3—3 of Figure 1.

The various novel features of my invention will be apparent from the following description and drawings and will be particularly pointed out in the appended claims.

Although my invention is not limited in its application to solid fuel, I will describe same in connection therewith, it being understood that liquid fuels may be treated in the same or similar manner.

In ordinary producer gas practice, wherein solid fuel is used, a sub-stratum of said fuel is furnished with sufficient oxygen to burn, the products of combustion therefrom being cooled by heating the upper stratum. In this heating action the tendency is to crack very small particles of coal from the upper bed, and these small particles are conveyed in the streams of products of combustion into washers, scrubbers, and the like. The percentage of fuel carried away in this shape is enormous, and in most cases it is necessary to positively extract this coal dust by means of washers and scrubbers, which deprives the gas of its sensible heat. As may be appreciated, this sensible heat is relatively large and must be considered seriously as a big factor, because the higher the temperature of a substance which is to be oxidized, the quicker will this oxidation take place; for example if iron is heated to 2400° F. and a stream of air is forced through it, the iron, and particularly

the carbon in it, will burn or oxidize, and the temperature of the molten mass will rise to as high as 3600° F., proving that the rapid oxidation is combustion in this case; but no one ordinarily would claim that iron is a fuel. The point which I wish to emphasize in this connection is that the 2400° in the above mentioned case in iron is analogous to the sensible heat in the gas as it leaves the producer.

Furthermore, in the ordinary producer plant, water seals are frequently introduced, as well as streams of steam, for the purpose of measurably cooling the burning stratum of coal, and thus preventing what is commonly known as slagging, which always occurs where the stream of air passes up through the interstices between the coal and takes a definite path. For this reason the ordinary producer must be stoked very frequently and caking prevented as much as possible. In addition to this, the common forms of producer plants receive air and discharge gas at a very low velocity, which necessitates a large, cumbersome receptacle, as well as large and expensive ducts. These are facts which commonly exist in the production of gas from solid fuel as practised generally today.

In connection with my invention, liquid or solid fuel in a finely divided state is subjected to a relatively rapidly moving heating medium or flame in which the finely divided fuel particles remain suspended until gassified, the apparatus used in connection with the practice of my method of producing gas being simple, inexpensive, efficient, and occupying a relatively small amount of space.

By referring to the figures of the drawings, it will be noted that I have shown a receptacle 10 provided with a supply chute 11, said receptacle 10 having an outlet passageway 12. Rotatably mounted within the receptacle 10 is shaft 13 having a feeding screw 14 for forcing the solid fuel downwardly in the receptacle 10 and to prevent clogging therein. Secured to the lower end of the shaft 13 is a movable conical grinding member 15 co-operating with a stationary grinding surface 16, by means of which the coal, we will assume is the fuel being used, is ground into a finely divided state. The degree of fineness into which the coal is ground may be varied by manipulation of adjusting screws 17 which pass through laterally extending arms of a support 18 which may be

fastened to receptacle 10 and bear against portions of a bracket 19 secured to the shaft 13 by set screws 20. The fuel after having been ground into a finely divided state 5 passes downwardly through the outlet passageway 12 into a receptacle 21, in which the fuel is treated and suspended in a heating medium, such as an extremely hot flame, whereby the fuel is gasified, where- 10 upon the gas and products of combustion pass downwardly through a conduit 22 into a relatively large tank 23 from which the gases pass through a pipe 24 into a washer, scrubber, or any other suitable cleaning de- 15 vice 25.

The receptacle 21 is preferably made of fire-clay and is in the form of a cylinder closed at the top. The cylindrical receptacle 21 near the bottom thereof is provided with 20 openings through which a plurality of burners 26 extend, said burners preferably entering the cylindrical receptacle 21 in substantially a tangential relationship, or at least in a position causing the heating medium or 25 flame issuing from the burners 26 to take a swirling action around in the receptacle 21. As appears from the drawing, the entrance to the conduit 22 is at a higher level than the region supplied by the burners 26. These 30 burners 26 are connected by a ring-shaped pipe 27, which is fed with a mixture of gas and air, the air under proper pressure being forced through a pipe 28, into which leads a gas supply pipe 29. The air passing through 35 the pipe 28 may have an injector action for drawing gas through the pipe 29 down into the ring-shaped pipe 27 and out through the burners 26. For supplying the air through the pipe 28, a convenient form of rotary pump 40 is provided, pipe 28 forming the exhaust for the pump 30. The supply of air is furnished through the inlet 31 to the blades of the rotary member of the pump, which blades or fans are held against the inner periphery 45 of the pump casing. Air being forced in through the inlet pipe 31 will cause the rotary member of the pump 30 to revolve and the air to pass out through the pipe 28.

In the operation of the device, the gas will 50 be turned on, as well as the air, and the burners 26 will be lighted as in an ordinary melting furnace, and when sufficient heat is generated, the coal dropping down through the passageway 12 in a pulverized form will be 55 swirled in a heat medium or flame, the temperature of which may be anywhere between 2800° to 3300° F. It readily will be seen that, depending upon the velocity of the flame, the heavier particles would be forced to the per- 60 phery of the cylindrical receptacle 21, and it is conceivable that if the feed of coal was extremely rapid the particles might build up on the walls of the receptacle 21, but the flames project against the sides and conse- 65 quently this coal would be very rapidly con-

verted into a gas. Depending, however, upon the grade of pulverization, it can be seen that the greater portion would be held suspended in the swirl and that each small particle would be surrounded by flame or products of combustion which are at a very high temperature. The higher the temperature, the quicker will be the gasification. As a result of actual experiment, I have found that the gasification process continues at a very high rate of speed, it being possible to make the resulting gas richer or leaner at will. This production of gas is not to be misinterpreted for an ordinary combustion of powdered coal, because in all forms this process has been the straightway projection of powdered coal and flame, and even with very high pressures, giving high velocities, particles of coal would have a definite trajectory which would cause them soon to arrive at a velocity insufficient to overcome the force of gravitation. In this swirl, during actual operation, I have counted as many as six definite layers, and to illustrate how long the coal must be suspended in the terrific temperature under these conditions, it is necessary only to visualize the average diameter of the spiral thus formed to be one foot, the average circumference, therefore, being, roughly speaking, three feet. Six such layers would mean that the coal particles would be suspended for eighteen feet of travel in a cylinder having as small a diameter as one foot. The gas expanded from the coal and the products of combustion from the three burners 26 take a path down through conduit 22 into a relatively large tank 23, the comparatively rapid movement in the conduit 22 being reduced to an exceedingly slow movement in tank 23 because of the very much greater diameter of the latter. Assuming that all of the carbon has been expended from the coal in the cylindrical receptacle 21, the products of combustion and gases would contain ash, and the purpose for passing the rapidly swirling gases into the large receptacle 23 is to reduce the velocity to give the ash as much time as possible to gravitate to the bottom of the tank 23, which is provided with a water seal 32 and from which the ash may be extracted without permitting the gas to escape. As stated before, the gases pass out of the tank 23 through a pipe 24 into any suitable receptacle 25, which may contain a scrubber or washer, or both.

In connection with the conversion of fixed carbon into gas, it might be stated that the coal industry, at least that part of it which furnishes coal gas, refers to the coal as having a content of 38 per cent of volatile matter. This means that 38 per cent of the fuel will 125 distill off as gases and vapors. The balance will be coke or fixed carbon and ash. This is due to the fact that as soon as the gas is expanded from the coal, a porosity is set up which makes it an exceedingly great non- 130

conductor of heat. Therefore, during the formation of coke, the latter becomes porous and hence a poor conductor of heat, so that it would require a disproportionately greater 5 amount of heat energy to distill off the carbon. However, if the coal is originally broken up into fine particles and each particle surrounded with a terrifically highly heated substance, the question of poor conductivity does not enter measurably, and hence the sharp line drawn between fixed and volatile carbon must disappear.

In connection with the swirling mixture of flame and coal granules, the heavy granules 10 will inevitably be forced outwardly and kept there by the centrifugal force; that is, they will be propelled a little, probably rolled along the bottom if heavy enough, and again picked up by the stream, so that the larger 15 particles will remain in the heated chamber considerably longer than the lighter particles. The gas passes out of the coal, and being several thousand times lighter, will follow the course down through the central 20 outlet conduit 22. The particles which are lighter will not be forced violently against the cylindrical receptacle 21 and will remain suspended in the moving stream.

It will be noted that the rotary member of 25 the pump 30 is mounted upon the upper end of the shaft 13. This rotary member is mounted on the shaft for the purpose of synchronizing the volume of air required for the combustion at the burners 26 with the 30 amount of coal fed through the passageway 12. It will be apparent that the more air admitted into the pump inlet 31, the greater will be the revolutions of the rotary member of the pump 30, and consequently the shaft 35 13, which is the means for harmonizing the coal supply and the air and gas supply because the air from the outlet pipe 28 will be supplied past the end of pipe 29 having an 40 injector action upon and drawing the gas 45 through said pipe.

It is my intention to cover all modifica-

tions of the invention falling within the spirit and scope of the following claims.

I claim:

1. In gas generating apparatus, in combination, a gas generating receptacle, means for supplying finely divided carbon to said receptacle, means for supplying a flame under pressure to hold said carbon in suspension, a conduit for conducting the combustible gas 55 produced from said receptacle, said conduit having its communication with said receptacle at a level higher than said flame supply means, and synchronously operating mechanical means for controlling said carbon 60 supplying means and said flame supplying means.

2. In gas generating apparatus, in combination, a gas generating receptacle, means for supplying fuel in a finely divided state to 65 said receptacle, means synchronized with said fuel supplying means for supplying a swirling flame to said fuel at the bottom of said receptacle to cause said fuel to be suspended until gasified, means for conducting the combustible gas produced from said receptacle, said means having its communication with said receptacle at a higher level than the region of said swirling flame, a tank connected 70 with said receptacle through said means, said tank being below said receptacle and of larger capacity than said receptacle, whereby the velocity of the products of gasification will be reduced to permit the deposit of ash.

3. A gas generator for producing combustible gas comprising, in combination, a cylindrical gas generating receptacle having its axis vertically placed, mechanical means for supplying finely divided carbon fuel to said receptacle, means for supplying air under 80 pressure tangentially of said receptacle, and mechanical means for synchronously controlling the supply of fuel and the supply 85 of air.

Signed at New York, New York, this 27th 90 day of January, 1920.

GEORGE L. REICHELM.
